UNITED STATES PATENT OFFICE.

BENJAMIN F. OLDMIXON, OF PITTSFIELD, MASSACHUSETTS.

TERMINAL CONNECTER.

Application filed September 20, 1920. Serial No. 411,619.

This invention relates to certain improvements in terminal connectors, and is particularly designed and peculiarly adapted as a spark plug connector for internal combustion engines.

The main object of the invention is the production of such a connector of simple and comparatively inexpensive construction, which may be easily, quickly and conveniently attached to an electrode of a spark plug, or other terminal, such attachment while having a certain flexibility, being relatively permanent as against the ordinary jars and other conditions incident to the ordinary use of an engine, and which connector may, when desired, be easily, quickly and conveniently removed from attachment to said electrode or terminal.

Other objects and advantages relate to the details of construction of the device as will more fully appear from the following description taken in connection with the accompanying drawings, in which:

Figure 1 is a sectional view of the device.
Figure 2 is an elevation of the body portion of same.

Figure 3 is an elevation of the movable jaw.

Figures 4, 5, 6 and 7 are respectively elevations of the spring, screw plug, encased conductor and stop pin.

The device as shown, consists of a tubular casing or body —1— having one end flattened and transversely perforated to form an elongated slot —2—. Within the tubular portion of the casing —1— is arranged a movable jaw —3— as shown in the form of a cylinder, having its front end formed with intersecting V-shaped grooves adapted to coact with the stationary jaw —4— formed by the laterally extending flattened end of the tube, or body —1—.

For the purpose of normally tensioning the jaw —3— a spring —5— is arranged within the casing —1— at the rear of the jaw —3—, the spring having its rear end in contact with a screw plug —6— having a threaded engagement with the threaded interior of the tube —1— to properly position and compress the spring in the original operation of assembling the device.

The wire, or conductor —7— suitably encased in insulating material —8— is inserted within the rear end of the tube or casing —1— and may be secured therein in any suitable manner, as for instance, by

solder or other suitable material —9—, which may have low fusing temperature, and for this purpose the tube —1— is provided with an opening —10— at the rear of the screw plug —6— for the passage of solder or other suitable attaching material after the encased conductor —7— has been properly placed within the tube —1—. However, any other suitable means of attaching the conductor for suitable electrical connection with the movable jaw —3— may be used.

Preferably, a tube —11— of insulating material is fitted over the casing —1— and the encased conductor —7— to protect the same against short circuiting by contact with the motor or other adjacent conducting parts.

The movable jaw —3— is provided with a transverse opening, or bore —12— for the reception of a stop pin —13— which may be secured therein in any suitable manner to limit the rearward movement of the movable jaw and also to cooperate with the walls of the slot —2— to hold the member —3— against turning relatively to the conducting tube —1— and to afford means whereby the member —3— may be moved inwardly against the action of the spring —5— to release the jaws from engagement with the terminal —14—.

The device so constructed is adapted for use in connection with any suitable terminal, such as the terminal —14— shown, which may form a portion of a spark plug or other suitable device.

It will be readily apparent that the attachment of the terminal connector shown to the terminal —14— may be easily and quickly effected by the use of one hand, and that disconnection is equally as easily effected, but that the gripped jaws maintain the attachment as against ordinary conditions of use.

It will be understood that various changes and modifications may be made in the details of the structure without departing from the invention as set forth in the appended claim.

What I claim is:

A terminal connection of the character described comprising a tube of conducting material having one end formed with an elongated slot closed at its outer end to form a jaw and having a restricted inner end portion, the inner end of said conducting tube

100

105

110

being threaded internally, a screw plug adjustably engaged with the internal threads of the conducting tube, an insulated electric conductor having an insulated portion secured in the inner end of the conducting tube and an adjacent bared end portion secured in the conducting tube in electric connection with the latter and the screw plug, a movable jaw slidable endwise in the outer end of the conducting tube and lengthwise of said slot toward and from the first-named jaw and provided with a serrated outer end face cooperating with said first-named jaw for gripping and releasing an electrical terminal between and from said jaws; a coin-

pression spring between the inner end of the sliding jaw and screw plug for urging said sliding jaw toward the first-named jaw with a force dependent upon the adjustment of the screw plug, and means on the sliding jaw projecting into the restricted inner end portion of the slot of the conducting tube for holding the second-named jaw against rotation and whereby the sliding jaw may be moved inwardly and thereby released by hand against the action of the spring.

In witness whereof I have hereunto set my hand this eighth day of September, 1920.

BENJAMIN F. OLDMIXON.
